The ornamental design for a container closure device, as shown and described.

DESCRIPTION

FIG. 1 is a front view of a container closure device showing one embodiment of my new design;

FIG. 2 is a rear view thereof;

FIG. 3 is a top plan view thereof;

FIG. 4 is a bottom plan view thereof;

FIG. 5 is a left side elevational view thereof, the right side elevational view being a mirror image thereof;

FIG. 6 is a perspective view thereof seen from the bottom; and,

FIG. 7 is a cross-sectional view thereof taken along the cutting plane 7-7 in FIG. 3.

The invention relates to a container closure device, for example, a bottle cork for containers such as bottles for sparkling wine, soda, and other carbonated beverages. The usage is such that first, a fitting member rotatably attached to the main body is rotated and a tight seal part of the body is applied to the bottle mouth. Thereafter, the fitting member is brought back to the original position while pressing the body to the bottle mouth, then is engaged with the fitting engagement part provided in the bottle mouth, and then the fitting member is fitted with the bottle mouth, thereby closing the bottle mouth.
